(57) **CLAIM**

The ornamental design for an electronic bass drum, as shown and described.

DESCRIPTION

FIG. 1 is a perspective view of an electronic bass drum showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is a perspective view thereof, showing the state while in use.

The broken lines illustrate portions of the electronic bass drum that form no part of the claimed design. The broken lines shown in FIG. 9 are included for the purpose of illustrating environmental structure and form no part of the claimed design.
